UNITED STATES PATENT OFFICE.

BENJAMIN C. BRADLEY, OF ALLIANCE, OHIO.

INCANDESCENT VAPOR-BURNER.

SPECIFICATION forming part of Letters Patent No. 650,368, dated May 29, 1900.

Application filed April 7, 1899. Serial No. 712,092. (No model.)

To all whom it may concern:

Be it known that I, BENJAMIN C. BRADLEY, a citizen of the United States, residing at Alliance, in the county of Stark and State of Ohio, have invented certain new and useful Improvements in Incandescent Vapor-Burners; and I do hereby declare that the following is a full, clear, and exact description of the same, reference being had to the annexed drawings, making a part of this specification, and to the figures of reference marked thereon, in which—

Figure 1 is a side elevation showing a portion of the globe broken away and showing parts in vertical section. Fig. 2 is a section on line *b b*, Fig. 1. Fig. 3 is a section on line *a a*, Fig. 1. Fig. 4 is a transverse section of the corrugated thimble, showing the mantle properly located thereon. Fig. 5 is a view showing the corrugated thimble placed on the burner-tube, also showing a portion of the mantle properly located with reference to the corrugated thimble, showing a portion of the thimble and burner-tube broken away. Fig. 6 is a side elevation showing the top or upper portion of the lamp proper removed. Fig. 7 is a view looking from the right-hand side of Fig. 6, except that the globe is removed. Fig. 8 is a top view of the mixing-chamber, showing the supporting-pipe, also showing top view of feed-chamber. Fig. 9 is a transverse section on line *x x*, Fig. 1. Fig. 10 is a transverse section on line *y y*, Fig. 1. Fig. 11 is a bottom or underside view of a screw-threaded flange, also showing the globe-supporting arms properly located with reference to said flange. Fig. 12 is a view showing the screw-faced flange, also showing the globe-supporting arms and the integral thimble connected to the screw-threaded flange or formed integral with said flange. Fig. 13 is a detached view of one of the globe-supporting arms. Fig. 14 is a view of the float, showing the different parts connected to said float to automatically operate the needle. Fig. 15 is a view showing my invention applied to a stand-lamp. Fig. 16 is a view showing the feed-pipe connected to the stand-pipe, which is a slight modification from that shown in Fig. 1. 50 Similar numerals of reference indicate corresponding parts in all the figures of the drawings.

In the accompanying drawings, 1 represents the supply-pipe, which is connected to a suitable reservoir of any desired kind or style, 55 which supply-pipe extends upward between the mantles and is connected at its upper end to the upper end or portion of the stand-pipe 2, which stand-pipe is provided with an enlarged portion 3, as shown in Fig. 2, at its upper end, which enlarged portion is connected to the mixing-chamber 4, or, if desired, said stand-pipe and mixing-chamber may be formed integral.

To one side of the stand-pipe 2 is located 65 the air-supply pipe 5, said air-supply pipe being also formed integral with the mixing-chamber 4 at its upper end, but the lower portion being formed separate, so that it may be removed for any purpose and may extend 70 downward, as illustrated in Figs. 1, 6, and 7.

To one side of the mixing-chamber 4 is located the mixing chamber or passage 6, which chamber or passage is located to one side of the air-conveying tube 5 and is a continuation 75 of the air-conveying tube.

As fuel is conveyed upward through the supply-pipe 1, which passes the burner or burners of the lamp proper, gas is produced or generated, which gas is conveyed to the top 80 or upper end of the stand-pipe 2 and on top of the float 7, which float is located in the stand-pipe 2, as illustrated in the drawings.

It will be understood that in use when fuel is first supplied to the lamp proper it will find 85 its way to the bottom of the stand-pipe, which will cause the float to be located at the upper portion of the stand-pipe or in substantially the position shown, it being understood that the rods 8 will prevent said float from 90 dropping to the bottom or lower end of the stand-pipe in the event the fuel should be removed therefrom and that said float is only to have a limited movement up and down in the stand-pipe, which limited movement operates upon the pivoted yoke-lever 9, which pivoted yoke-lever is connected to the regulating-needle 10. The float is so arranged that its normal position will close the needle 10 and cut off the supply of gas, and when 100 the oil below the float has become converted into gas, or a portion of said oil, the float may be permitted to fall or move downward, which downward movement carries with it the yoke-

lever 9 at the point or place where the rods 8 are connected and throws or forces the downward portion 11 of the yoke-lever 9 outward, thereby allowing the gas to escape, as 5 hereinafter described.

For the purpose of closing the needle 10 the spring 12 is provided, which spring is located and arranged substantially as shown in Fig. 1, and, as shown, it is located between 10 the cap 13 and the end of the needle 10, said needle being provided with the reduced portion 14, around which the spring 12 is located.

For the purpose of regulating the tension 15 of the spring 12 the disk 15 is located in the cap and the screw 16 passed through the cap and against the disk.

As gas is generated it finds its way to the chamber or receptacle 17 and is conveyed 20 from said chamber or receptacle through the passage 18 and into the chamber or passage 6, at which place air comes in contact with the gas and the air and gas conveyed to the mixing-chamber 4, and for the purpose of providing 25 a means for thoroughly mixing the air and the gas the deflecting plates 19 and 20 are provided, the plate 20 being located above the plate 19 and said plate 20 being connected to the mixing-chamber 4 at a point 30 below the gas-pipe 21, and the plate 19 is connected at the opposite side of the mixing-chamber, by which arrangement the air and gas are carried first under the plate 19, thence 35 backward over the plate 19 and under the plate 20, and thence forward over the plate 20 and into the gas-pipe 21.

It will be understood that by locating the mixing-chamber directly over the burners 40 said mixing-chamber becomes heated, thereby bringing the gas into better condition to be 45 burned by thoroughly mixing the gas and air together, which mixture is brought about by conveying the gas and air back and forth in the mixing-chamber. It will also be understood 50 that by my peculiar arrangement of the mixing-chamber and the location of the plates 19 and 20 the volume of the gas and air is varied, the volume being expanded and contracted during its passage through the mixing-chamber.

The gas-tube 21 is extended downward, and its bottom or lower end is connected to the receiving-chamber 22, which receiving-chamber is located below the mantles 23, it being 55 understood that any desired number of mantles may be provided, reference being had to the number of burners designed to be used. From the receiving-chamber 22 extends upward 60 the burner-tubes 24, to which burner-tubes are connected the corrugated thimbles or bands 25, and over which corrugated thimbles or bands is located the bottom or lower end of the mantle 23. To the receiving-chamber 22 is connected the tube 26, which 65 tube extends downward through the receiving-chamber and below said receiving-cham-

ber, as illustrated in Fig. 1. Around the tube 26 is located the thimble 27, which thimble is provided with the handle 28 and screw-threaded flange 29, said screw-threaded flange 70 and handle being preferably formed integral with the thimble 26.

For the purpose of providing a support for the screw-threaded flange, together with the different parts belonging thereto, the tube 26 75 is provided at its bottom or lower end with the flange 30.

To the bottom or under side of the receiving-chamber 22 are pivotally connected the arms 31, which arms extend downward, and 80 to their bottom or lower ends are pivotally connected the globe-supporting arms 32, the outer ends of which are provided with the upwardly-curved flanges 33, which upwardly-curved flanges are for the purpose of engaging and holding the globe 34.

The object and purpose of providing the screw-threaded flange 29 is to provide a means for moving the globe-supporting arms back and forth for the purpose hereinafter de- 90 scribed.

When it is desired to remove the globe 34, the screw-threaded flange 29 is first rotated in the direction that will force the arms 32 outward, after which the globe 34 is slightly 95 elevated, so as to bring the curved ends 33 below the bottom of the globe, after which the screw-threaded flange 29 is rotated in the opposite direction, which moves the globe-supporting arms inward, and when said globe-supporting arms have been brought inward a sufficient distance the globe 34 can be moved 100 downward and entirely removed from the lamp proper.

For the purpose of providing a means for 105 starting the lamp the upper side of the top plate 35, which is the upper plate of the receiving-chamber 22, is provided with the grooves or depressions 36, which grooves or depressions may be arranged and located as 110 shown in Fig. 10, said grooves or depressions being for the purpose of receiving alcohol or light material, which is forced up through the tube 37 by any suitable injector, and for the purpose of conducting the alcohol to the depressions or grooves the cap 38 is provided, which cap is supported in proper position by means of the connecting bars or feet 39, (see Fig. 10,) and for the purpose of forcing the alcohol away from the top or upper end of 120 the tube 37 the cap 38 is provided with the inverted cone 40, said cone being located and arranged substantially as shown in Fig. 1.

In Fig. 15 I have shown my invention as applied to a stand-lamp. In order to provide 125 a circulation between the stand-pipe 2 and the feed-pipe 1, said feed-pipe may be connected to the stand-pipe by means of the short tube 41, which short tube connects the two pipes together and forms a communication between 130 the stand-pipe and the feed-pipe 1. This feature is not illustrated except in Fig. 16;

but it will be understood that when connected as just described the feed-pipe 1 is to be bent or brought into such a position that it can be connected to the stand-pipe.

5 For the purpose of providing a means for removing the supply-pipe 1 for the purpose of removing any sediment that may collect therein said pipe is connected by means of the screw-threaded couplings 42 and 43.

10 The hydrocarbon used in my lamp is kerosene-oil, or what is more commonly known as "coal-oil," but it will be understood that other hydrocarbons may be used without departing from the nature of my invention; but

15 I prefer to use the common kerosene-oil, and the construction above described is well adapted to the use of common kerosene-oil.

For the purpose of providing a support for the dome or cap 1^a the bars or tubes 2^a are 20 provided, said bars or tubes being connected to the top or upper side of the mixing-chamber 4.

It will be understood that by arrangement of the float the needle 10 will not move so as 25 to open its valve until the gas is generated or heated to a high enough temperature to make a very rapid combustion.

It will be understood that many slight modifications may be made without departing from 30 the nature of my invention, and hence I do not desire to be confined to the exact construction and arrangement shown and described.

Having fully described my invention, what I claim as new, and desire to secure by Letters

35 Patent, is—

1. The combination of a feed-pipe connected to and communicating with a stand-pipe, a float located within the stand-pipe, a lever connected to the float, a needle connected to 40 the lever, an air-supply pipe provided with a chamber at its upper end, a gas-chamber located around the chamber leading from the supply-pipe, a passage leading to the needle-chamber, a mixing-chamber provided with 45 plates, one of said plates located below the other and passages formed in the mixing-chamber, a gas-conveying tube leading from the mixing-chamber to the receiving-chamber, and a burner tube or tubes located above

the gas-retainer chamber, all arranged, substantially as and for the purpose specified. 50

2. A supply-pipe connected to a stand-pipe provided with a float, an air-passage pipe provided with a needle-chamber and a needle located within the chamber, means for operating the needle with the float, a mixing-chamber and means for conveying gas to the burners, substantially as and for the purpose specified. 55

3. In an incandescent vapor - burner, a stand-pipe provided with a float, a feed-pipe connected to the upper end or portion of the stand-pipe, an air-supply pipe located adjacent to the stand-pipe and provided with a chamber at its upper end, said chamber located above the stand-pipe, a needle-chamber and a needle located therein, said chamber and needle located at one side of the chamber 4, a passage leading from the chamber above the stand-pipe, and a mixing-chamber located above the burners, and the deflecting-plates 19 and 20 located within the mixing-chamber, and a pipe leading from the mixing-chamber to the receiving - chamber, and means for operating the needle, substantially as and for the purpose specified. 65 70 75

4. In a burner of the class described, a stand-pipe provided with a float, the rods 8 located as shown, the yoke-lever 9 connected to the regulating-needle 10, a feed-pipe connected to and communicating with the stand-pipe at a point above the float, a needle-chamber located above the stand-pipe, a passage leading from the needle-chamber and a mixing-chamber located above the burner, a gas-conveying tube leading from the mixing-chamber to a receiving-chamber located below the burners, and a burner or burners located above the receiving-chamber, substantially as and for the purpose specified. 80 85 9c

In testimony that I claim the above I have hereunto subscribed my name in the presence of two witnesses.

BENJAMIN C. BRADLEY.

Witnesses:

WILLIAM M. ROACH,
C. C. DAVIDSON.
